CURB TEMPLATE

Robert G. Ferris, Harvard, Ill., assignor to Starline, Inc., Harvard, Ill., a corporation of Illinois

Application January 23, 1939, Serial No. 252,497

2 Claims. (Cl. 25—118)

My invention relates to templates for use more particularly in connection with the building of animal stalls of the type comprising concrete floors and curbs and stall portions rising from the floor and having posts anchored in the curbs, these structures being commonly provided with stanchions located directly above the curbs. The invention relates more especially to templates for use in temporarily supporting the posts of the stall partitions in the proper position during the pouring and setting of the concrete in forming the curbs.

One of my objects is to provide a novel, simple and economical structure of template for the purpose set forth.

Other objects are to provide a template which may be used in connection with the producing of a stall structure of the general character above referred to the curb of which is of tapered form; to provide a template which may be used either in the producing of a curb having substantially parallel sides, or a tapered curb of such a stall structure, particularly where the mold boards used for forming the curb are of rectangular cross section as commonly provided whereby their upper edges when installed in the position of use, extend horizontally if the mold boards are vertically disposed as in the form of a curb having substantially parallel side walls, or at an angle to the horizontal if the mold boards extend in inclined position as in the forming of a tapered curb; to provide a template with means by which the mold boards may be readily positioned in properly spaced relation; to provide a template which will permit of the proper smoothing of the top surface of the concrete of the curb at the template while the latter is in place; and other objects as will be manifest from the following description.

Referring to the accompanying drawings:

Figure 1 is a view in cross-section of an animal stall of a construction which may be built by the use of my improved template.

Figure 2 is a perspective view of my improved template.

Figure 3 is an enlarged fragmentary vertical sectional view of a portion of the stall structure showing the template in its related position to the post.

Figure 4 is a fragmentary perspective view illustrating a step in the building of the stall structure of Fig. 1 and utilizing my invention.

Figure 5 is a sectional view, somewhat in the nature of a diagram, of a portion of the structure shown in Fig. 4, the section being taken at the

line 5 on Fig. 4 and viewed in the direction of the arrow, with certain parts omitted.

Figure 6 is a view like Fig. 5 of a portion of the structure shown in Fig. 4, the section being taken at the line 5 on Fig. 4 and viewed in the direction of the arrow, with certain parts omitted.

Figure 7 is a view like Fig. 4 and of the structure therein shown, illustrating a variation in the step shown in Fig. 4 of producing the stall structure.

Figure 8 is a view like Fig. 4 illustrating a step in the producing of a stall structure of Fig. 1 modified to omit the bottom bars to which the stanchions are connected.

Figure 9 is a view like Fig. 4 illustrating a step in the producing of a stall structure and utilizing my invention, in which the curb thereof has substantially parallel sides; and

Figure 10, a sectional view, somewhat in the nature of a diagram, of a portion of the structure shown in Fig. 9, the section being taken at the line 10 and viewed in the direction of the arrow, with certain parts omitted.

Referring to the construction shown in Figs. 1-6, inclusive, which illustrates my invention in connection with the building of a line of animal stalls, the floor of the stalls, commonly made of concrete and extending continuously along the stalls, is represented at 11. At the forward edge of the floor is a feed-trough 12 the back edge of which is formed by a curb 13. At the rear edge of the floor 11 is a gutter 14, the trough 12, curb 13, and gutter being commonly cast separately from the floor and extending continuously along the stalls.

The stalls are formed of posts 15 spaced apart and embedded in the concrete of the curb 13, and parallel spaced apart stall-partitions 16 connected at their upper forward ends 17 to the posts 15 and at their lower rear ends anchored to the floor 11.

The stalls are commonly provided between the posts of each stall with stanchions (not shown) 45 to receive the necks of the animals positioned in the stalls.

The stanchions are hung at their upper ends, in a well-known manner, from frames (not shown) located between the posts 15 of the stalls, and 50 are connected at their lower ends to bottom bars 18 located between these posts, the connections of the stanchions with the frames and bottom bars being such as to permit the stanchions to have limited rotary and swinging movements.

In constructing the stall 5 the curb 13 would

be cast first. For this purpose mold boards 19-22 would be erected at the desired location, the lower mold-boards 19 and 20 set in vertical spaced apart position and the upper mold boards 21 and 22 converging upwardly to correspond with the desired taper of the curb 13 to be produced. Stakes 23 driven into the ground at opposite sides of the mold formed by the mold boards 19-22 and having upwardly converging surfaces 24 presented by wedge blocks 25 secured to the upper ends of the stakes, serve to prevent outward displacement of the mold-boards.

The mold-boards being in place the posts 15 are positioned in the molds to extend in the desired horizontally spaced relation. Where the stall structure includes a bottom bar 18 it is desirable, as a convenient means for properly spacing the posts 15, that this bar be positioned between the posts 15. When the bar 18 in the finished structure extends close to the top surface of the curb, it is supported, to serve merely as a post-spacing means, either by inverting the bar and in this position bolting it at the clips on its ends (the clip at one end being shown at 26) to the adjacent posts 15, as shown of the one clip 26, at 27 in Fig. 4, or by merely positioning the bar 18 at a higher elevation and securing it in place, as for example by the wire securing means shown at 28, as illustrated in Fig. 7.

The mold-boards 21 and 22 are cross-connected at their top surfaces 29, shown as at a right angle to their parallel sides, with means, located at each post 15 and holding these mold-boards in the desired inclined position and for positioning the posts 15. These means comprise my improved template shown at 30 which, in accordance with the illustrated embodiment of my invention, is formed of sheet metal presenting a plate-like body portion 31 having a longitudinally extending corrugation 32 to increase its strength and a bolt-hole 33 at its upper end midway between its ends. The lower edge portion of the body portion 31 is provided with a pair of flanges 34 at its ends extending at right angles to the body portion 31 and parallel with the longitudinal axis of the template, an opening 35 being provided in each flange 34. The lower edge portion of the body portion 31 is also provided, between the flanges 34, with a pair of flanges 36 extending at right angles to the body portion 31 but at angles to the longitudinal axis of the template and having apertures 37 therein, the flanges 36 converging downwardly toward the center of the template at such an angle as to cause these flanges to fit flatwise against the upper surfaces 29 of the converging mold-boards 21 and 22.

In cutting the metal of the plate to form the template it is recessed at 38, outer walls 39 of these recesses being spaced apart, at their lower ends, a distance equal to the distance between the outer faces of the mold-boards 21 and 22 at their upper portions, whereby when the template is applied to the mold-boards 21 and 22 the surfaces 39 will form a gauge for inclining these mold boards at the desired angle.

The templates, as will be understood, are placed cross-wise of the mold-boards 21 and 22 and secured in place thereto, as by nails 40 driven through the openings 37 into the mold-boards; and the posts 15 and templates secured together by the bolts 27 which extend through the posts and the apertures 33 in the templates.

The notching of the plate from which the template is formed to produce the flanges 36 is sufficiently deep to form a recess 41 extending above

the junctures of the flanges 36 with the body portion 31, and thus when the template is applied to position on the mold-boards 21 and 22 as described, a space between the template and the plane of the upper surface of the curb to be formed is presented.

The concrete to form the curb and anchor the lower ends of the posts 15 is poured into the mold at its top and smoothed off, the recesses 41 permitting of the proper smoothing of the concrete beneath the templates.

After the concrete is set the mold boards 19-22, stakes 23 and templates 30 are removed and the bottom bars 18 disconnected from the posts 15 and replaced thereon in the position they are to occupy in the finished structure (Fig. 1).

In utilizing the invention in accordance with the disclosure in Fig. 8, which relates to the constructing of a stall structure which does not have a bottom bar but provides other means (not shown) for connection with the lower ends of the stanchions, the templates 30 are provided one at each post 15 and are secured to the mold-boards 21 and 22 and to the posts as described 25 of the procedure illustrated in Figs. 1-7, the bolts 27 serving the sole purpose of securing the posts and templates together.

In constructing the parallel-sided curb of Figs. 9 and 10 and shown at 42, all of the mold-boards, 30 herein represented at 43 to 46, inclusive, for forming this curb and corresponding to the mold-boards 19-22, inclusive, are disposed vertically in the properly spaced relation; the posts 15 are positioned at their lower ends in the mold thus provided; the bottom bars 18, when used, are applied to the position they occupy in the finished structure and connected at their ends with the posts 15 by the bolts 27 which extend through the clips 26 and the posts 15, and the templates 30 applied to position on the mold-boards 45 and 46. The templates 30 are secured to the posts by the bolts 27 which pass through the apertures 33 in the templates and to the mold-boards 45 and 46, as by nails 47 driven through the apertures 35 in the flanges 34, into the mold-boards, the outer edges 48 of the flanges 34 serving as gauging means to properly space the mold-boards 45 and 46 apart.

The lower edges of the flanges 35 extend at an elevation above the flanges 34, this feature, together with the recesses 41, permitting of the smoothing of the upper surface of the concrete beneath the templates, which after the concrete has become set are removed, as are also the mold boards.

What I claim as new and desire to secure by Letters Patent, is:

1. A template, for the purpose set forth, having substantially horizontal spaced surfaces for seating the template on the upper edges of substantially vertical mold boards and inclined surfaces set in from said first-referred-to surfaces for seating the template on the upper edges of upwardly converging mold boards, said inclined surfaces being located in a plane above said horizontal surfaces, and the lower edge of the template between said inclined surfaces being recessed, whereby in the use of either of said surfaces space for troweling is provided between the template and the top of the concrete molded between the mold boards.

2. A template, for the purpose set forth, having substantially horizontal spaced seating surfaces and upwardly diverging inclined seating surfaces set in from said first-referred-to surfaces, said

inclined surfaces being located in a plane above said horizontal surfaces each of said substantially horizontal surfaces for seating on the upper edge of a substantially vertical mold board and each of said inclined surfaces for seating on the upper edge of an upwardly inclined mold board the low-

er edge of the template between said inclined surfaces being recessed, whereby in the use of any two of said surfaces space for troweling is provided between the template and the top of the concrete molded between the mold boards.

ROBERT G. FERRIS.
